DESIGN FOR A FRAME FOR MIRRORS

Max H. Storch, Belle Harbor, N. Y.

Application November 23, 1944, Serial No. 116,511

Term of patent 3½ years

(Cl. D86—10)

To all whom it may concern:

Be it known that I, Max H. Storch, a citizen of the United States, residing in Belle Harbor, county of Queens, and State of New York, have invented a new, original, and ornamental Design for a Frame for Mirrors, of which the following is a specification, reference being had to the accompanying drawing, forming part thereof.

Figure 1 is a front view of the frame for mir-

rors showing my new design. The back of the frame is substantially like the front shown.

Figure 2 is a side elevation of the frame for mirrors shown in Figure 1.

I claim:

The ornamental design for a frame for mirrors, substantially as shown and described.

MAX H. STORCH.
